ELECTRIC SELECTING DEVICE RESPONSIVE
TO IMPULSES

William Gordon Foster, London, England, assignor to Telephone Manufacturing Company Limited, London, England, a British company

Application March 24, 1952, Serial No. 278,162

Claims priority, application Great Britain
April 2, 1951

5 Claims. (Cl. 340—168)

1

This invention relates to electric selecting devices responsive to impulses.

Electric selecting devices responsive to impulses are well known in the telephone and other arts for counting a number of impulses and for performing or causing the performance of desired operations in dependence upon the number of impulses. They are mainly of one or other of two kinds, namely of step-by-step electro-mechanical switches or of relay chains.

The present invention is concerned with an electric selecting device responsive to impulses, which partakes more of the nature of a relay selecting chain rather than of a step-by-step electro-mechanical switch, and makes use of so-called selective relay units to perform the operation of selection in response to impulses and, it may be, to perform or to cause to be performed a desired operation.

The term "selective relay unit" denotes a device which consists of an electro-magnetic relay having a plurality of sets of contacts, a finger magnet being associated with each set of contacts, each finger magnet, when energized serving to interpose a finger between its associated set of contacts and the armature of the relay so that only the set of contacts associated with the energized finger magnet is operated upon when the armature of the relay is actuated.

In our patent specification Serial No. 159,321 we have described an electric selecting device comprising selective relay units and responsive to impulses. The electric selecting device therein described comprises ten selective relay units and is capable of counting up to a maximum of ten impulses. In the system therein described, the selective relay units have other duties to perform in dependence upon the number of impulses counted, that is the ten selective relay units are required to connect a particular circuit to any one of one hundred other circuits, each selective relay unit being capable of connecting the said one circuit to any one of ten such other circuits. When such is the requirement, there is no objection to the provision of ten selective relay units. When, however, the maximum number of such other circuits is twenty arranged in ten numerical groups of two circuits per group a requirement which can be satisfied by two selective relay units, it is manifestly undesirable to have to provide ten selective relay units, eight of which are provided for no other purpose than that of counting impulses.

The present invention, by permitting the finger magnets of the selective relay units to take part

2

in the numerical selecting operation makes it possible to perform or to control the performance of any one of $2n$ operations by means of two selective relay units each having n finger magnets.

According to the present invention, an electric selecting device comprises two selective relay units, each having n finger magnets, said selective relay units being adapted to be operated in alternation in response to impulses and each, when operated, closing a circuit for a finger magnet of the other, so that the finger magnets of one selective relay unit are operated in succession in response to odd-numbered impulses and those of the other are operated in succession in response to even-numbered impulses, the electric selecting device being thus able selectively to perform or to control the performance of any one of $2n$ operations.

20 The invention is illustrated in the accompanying drawings of which Fig. 1 illustrates a selective relay unit and Fig. 2 is a circuit diagram illustrating the invention.

A selective relay unit (hereinafter referred to 25 as a SRU) as illustrated quite diagrammatically in Fig. 1 consists of five sets of contacts numbered respectively 1-5, an armature AR, an energizing magnet SR and five fingers, shown as points, one to the left of each set of contacts.

30 A finger magnet (not shown) is associated with each finger. If, with all the fingers in the positions indicated the armature AR is operated, it will be unable to operate any of the contacts. If, on the other hand, any finger is moved to 35 the right so as to come between its associated bank of contacts and the armature, and after this the armature is operated, the bank of contacts concerned will be operated. Thus a means is provided for selecting, by energization of any 40 one of the finger magnets, any one of the sets of contacts 1-5.

Referring now to Figure 2, an electric selecting device responsive to impulses is shown. This 45 consists of two SRU's and a number of other relays and circuits.

One of the SRU's, namely that given the general reference SRU1, is represented by its energizing magnet SR1, its armature AR1, five finger magnets FM1, FM3, FM5, FM7, FM9, five fingers respectively f1, f3, f5, f7, f9, and five sets of contacts sr1(a). SRU1 also has certain other contacts, which are operated every time an armature AR1 operates, indicated by the reference sr1 followed by a "solidus" and a number. SRU1 may also have other contacts

sr1(b) similar to *sr1(a)* which are operated only when a finger magnet is interposed between the contacts and the armature. These per se form no part of the invention. A second SRU namely that shown generally as SRU2, is similarly represented in Fig. 2 by the same reference but with the numeral 1 replaced by the numeral 2.

Relays B and C are retarded release relays and relay IP is an impulse relay, responsive to interruptions by the line circuit for delivering impulses from its contact *ip1* to the electric selecting device constituted by the two SRU's.

All the relay contacts in Figure 2 are represented in their normal (at rest) positions and all the coils are de-energized. Operation is as follows: switch S, which if the electric selecting device forms part of a telephone system, may be the switch hook of a subscriber's telephone, is operated and a circuit closed from earth through the dial contacts D, switch S, relay winding IP to negative. Relay IP at its contact *ip1* closes an obvious circuit for relay B. These operations are preparatory and beyond the closure of contacts of relay B have only one effect, that is the closure of a circuit from earth, through contacts *b3* (operated) *sr2/2*, *sr1/1* (at rest), and finger magnet FM1 to negative. Finger magnet FM1 moves finger *f1* between contacts *sr1(a)* number one and armature AR1. When the dial D is operated the line circuit is interrupted a certain number of times, depending on the value of the digit being dialled, and the relay IP is de-energized a corresponding number of times.

The first time relay IP de-energizes it closes a circuit from earth via contacts *ip1* (back), *b1* (front) and *sw1* (back) for energizing magnet SR1. It also closes an obvious circuit for relay C. Both SR1 and C will become energized. SR1 operates its armature and thereby closes a circuit for finger magnet FM2, this circuit being from earth, via contacts *b2* (front), *c2* (front) *sr1(a)* number one, finger magnet to negative.

SR1 also closes a holding circuit from earth by way of contacts *b3* (front) *sr2/2* (back), *sr1/1* (front), through winding of relay SW and the winding of SR1. Relay SW does not operate in this circuit as it has earth connected to both sides of its winding, that is via the connection just traced to one side, and from earth, via contacts *ip1* (back), *b1* (front), and *sw* (back) to the other side.

When relay IP re-operates the short circuit is removed from relay SW and this relay now operates.

When relay IP releases for the second impulse a circuit is completed for energizing winding SR2, this circuit being from earth via *ip1* (back), *b1* (front) *sw1* (front), and *sr2/1* (back). SR2 operates its armature AR2, and by reason of the fact that finger *f2* is between contacts SR2(a) number two and armature AR2, these latter contacts are closed and a circuit is thereby completed for finger magnet FM3, the circuit being similar to that for FM2. SR2 also transfers itself into a holding circuit by way of earth, contact *b2* (front), contact *sw2* (front) and make-before-break contacts *sr2/1* (front). At *sr2/2* it opens a circuit for relay SW and the holding circuit of SR1. SW is still held, however, in a circuit from earth by way of contacts *ip1* (back), *b1* (front) and *sw1* (front), to negative. SR1 de-energizes and closes at *sr1/2* an alternative holding circuit for SR2: this alternative holding circuit is from earth, via contacts *b2* (front), *sr1/2* (back), *sr2/1* (front) and the winding of SR2 to negative.

At the end of this second impulse, when relay IP re-operates, the circuit for relay SW is opened and this relay releases, SR2 however, remaining held.

In response to the third impulse SR1 again becomes energized and at contacts SR1(a) number three, closes a circuit for finger magnet FM4. It is thought unnecessary to trace the operations any further as they should be sufficiently clear from the description already given.

For the present description it may be supposed that only two impulses have to be counted. Under such a supposition we are now at the position that SR2 is energized with finger *f2* between contacts SR2(a) number two and armature AR2, and that these contacts are closed. Also contacts *sr2(b)* number two are closed. FM3 is energized but has no effect until SR1 should be operated in response to three impulses (which in the present supposition we have excluded).

Since no further impulses are to be received contact *ip1* will be held away from its resting position and relay C will consequently release after a short delay. Relay C at contact *c2* (front) will open the circuit for finger magnet FM3 and at contact *c2* (back) will close a circuit by way of contact SR2(b) number two for the performance or control of desired operation number two.

I claim:

1. An electric selective device responsive to impulses from a source of impulses, said device including two selective relay units each having a plurality of sets of contacts, an armature, an energizing coil, a plurality of fingers one associated with each set of contacts for interposition between said set of contacts and said armature, a like plurality of finger magnets one associated with each finger for interposing when energized its associated finger between a set of contacts and said armature, and connections between sets of contacts of each selective relay unit and finger magnets of the other selective relay unit so that each selective relay unit when energized closes an energizing circuit through one set of its contacts and one finger magnet of the other selective relay unit, said selective device further including means for directing impulses from said source in alternation to the energizing coils of said selective relay units.

2. An electric selective device as set forth in claim 1 wherein said means for directing impulses from said source to said energizing coils includes a switching relay having a changeover contact, a front contact and a back contact, a connection from the changeover contact to said source of impulses, a connection from said front contact to the energizing winding of one selective relay unit, and a connection from said back contact to the energizing winding of the other selective relay unit, and circuit means from said source of impulses through contacts of said selective relay units to said switching relay for operating said switching relay in response to even-numbered impulses from said source.

3. An electric selective device responsive to impulses from a source of impulses, said device including two selective relay units each having a plurality of sets of contacts, an armature, an energizing coil, a plurality of fingers, one associated with each set of contacts for interposition between said set of contacts and said armature, a like plurality of finger magnets, one associated with each finger for interposing when energized its associated finger between a set of contacts

and said armature, connections between sets of contacts of each selective relay unit and finger magnets of the other selective relay unit so that each selective relay unit when energized closes an energizing circuit through one set of its contacts and one finger magnet of the other selective relay unit, said selective device further including switching means for directing odd-numbered impulses from said source of impulses to the winding of one of said selective relay units and even-numbered impulses from said source of impulses to the winding of the other of said selective relay units.

4. An electric selective device as set forth in claim 3, wherein said switching means includes a switching relay having two windings, a change-over contact, a front contact and a back contact, a connection from the changeover contact to said source of impulses, a connection from said front contact to the energizing winding of said one selective relay unit, and a connection from said back contact to the energizing winding of the other selective relay unit, a further connection from said front contact to one of said two windings and a further connection from said back contact to the other of said two windings, said further connection from said back contact including a front contact on said one selective relay unit and a front contact on said other selective relay unit.

5. An electric selecting device responsive to impulses, comprising in combination a source of impulses, a first relay, a second relay, switching means, circuit means including said switching means for directing impulses from said source of impulses to said first and second relays in alternation thereby to operate them in alternation, a plurality of sets of contacts for each of said first and second relays, means for selecting 10 sets of contacts of said first relay one at a time, means for operating the selected set of contacts, means for selecting sets of contacts of said second relay one at a time, means for operating the selected sets of contacts, and means including 15 said sets of contacts of each said relay for operating the operating means of the other relay, whereby said first and said second relays effect a progressive selection of said sets of contacts.
